UNITED STATES PATENT OFFICE.

BERNARD C. MARGILETH, OF AURORA, INDIANA.

FIRE-ESCAPE.

SPECIFICATION forming part of Letters Patent No. 289,286, dated November 27, 1883.

Application filed September 13, 1883. (No model.)

To all whom it may concern:

Be it known that I, BERNARD C. MARGILETH, a citizen of the United States of America, residing at Aurora, in the county of Dearborn 5 and State of Indiana, have invented certain new and useful Improvements in Fire-Escapes; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to certain improvements in fire-escapes; and it consists in the improved structure, fully described hereinafter, whereby the application of the improvements to buildings is readily effected, the device presenting a neat appearance, and its effective operation secured when required.

20 In the accompanying drawings, Figure 1 is a front view of a window-frame, showing my device applied for operation; and Fig. 2 is a section.

25 A B C represent, respectively, the sill and side sections of a window-frame, upon the top bar, F, of which is constructed a rectangular case or receptacle, E. As the width of the top 30 of the window-frame is ordinarily insufficient for the requirements of the receptacle, I extend said receptacle by securing to the side sections, B C, of the frame, at their upper sides, blocks a b, to the top of which and to the top of the sections 35 B C is secured the top c of the case or receptacle. The front faces of the blocks a b and front edge 40 of the top c project beyond the plane of the window-frame, and beneath the top c is a cross-section, d, to the lower edge of which is hinged an angled door, e, consisting of the parts f g, the part f, when the door is in a closed position, constituting a portion of the front of the receptacle, while the part g constitutes a portion of the bottom thereof. A horizontal 45 shaft, G, within the casing E has its ends journaled in the blocks a b and rigidly mounted thereon, and two drums, H I, which revolve together. Around the drum I is wound a rope, i, which has one end fastened to the drum, while

the pendent end carries a flexible belt, j, which 50 is adapted to embrace the body of a person, to lower him when the rope is unwound. One end of a second rope, h, is secured to the drum H, but is wound around the same in a different direction from that on the drum 55 I, the said rope h being twice the length of the rope i. The disengaged end of the rope h passes through a rectangular opening, n, 60 formed in the bar F of the window-frame, and is connected to a block or plug, l, having a beveled edge, m, and adapted to be inserted and retained in the rectangular opening n, when 65 therein, by reason of its beveled edge bearing against a similar beveled face consisting of one of the beveled sides of the slot or opening. A 70 hand-ring, o, is connected to the lower side of the block l, to facilitate manipulation. Both 75 ropes being wound up on their drums, the operation of the device is as follows: The angular door is swung back, and the ring o is grasped to pull the block l from the opening n, and the 80 rope h is then unwound and passed to the ground its full length. During this revolution of the drums H I the rope i, with the belt j, has been turning with the drum I, it requiring a revolution in a reverse direction to effect 85 its unwinding. The belt j being passed around a person's body, or the end of said rope being attached to some article to be lowered, the person or article descends and unwinds the rope 90 i by gravity, and if it be a person he grasps the rope h, to regulate the speed of his descent. When the end of the rope i shall have reached the ground, about one-half of the rope h will have been wound up upon the drum H, leaving 95 sufficient unwound to effect the rewinding and ascent of the rope i by pulling on the rope h and revolving the drums.

It is intended that a gong or bell, M, located in the chambers a or b, (shown in dotted lines at the end of the case E,) is to be connected with one of the moving parts of the device, so that it will be known at all times when the same is used, and thus prevent any fraudulent use thereof.

I claim—

1. In combination, in a fire-escape, the receptacle or case arranged at the upper por-

tion of the window, and provided with a door, and two drums, II I, carrying ropes wound in different directions upon the same, and one double the length of the other, substantially as set forth.

2. The combination, in a fire-escape, of a receptacle or case arranged at the upper portion of the window, and provided with an angular door, and with two drums, II I, carrying ropes

wound in different directions upon the same, substantially as set forth.

In testimony whereof I affix my signature in presence of two witnesses.

BERNARD C. MARGILETH.
